UNITED STATES PATENT OFFICE.

WILLIAM SCHEURER, OF WEST NEW YORK, NEW JERSEY.

FAN ATTACHMENT FOR ROCKING-CHAIRS.

No. 884,212.

Specification of Letters Patent.

Patented April 7, 1908.

Application filed November 20, 1907. Serial No. 402,993.

To all whom it may concern:

Be it known that I, WILLIAM SCHEURER, a citizen of the United States, and a resident of West New York, in the county of Hudson and State of New Jersey, have invented a new and Improved Fan Attachment for Rocking-Chairs, of which the following is a full, clear, and exact description.

This invention relates to a fan attachment for rocking chairs, and the object of the invention is to provide an arrangement whereby a person sitting in a rocking chair will be automatically fanned as the chair rocks.

More specifically, the object of the invention is to provide improved means for driving the fan.

The invention consists in the construction and combination of parts, to be more fully described hereinafter and particularly set forth in the claims.

Reference is to be had to the accompanying drawings forming a part of this specification, in which similar characters of reference indicate corresponding parts in all the figures.

Figure 1 is a perspective of a rocking chair to which the invention has been applied; Fig. 2 is a front elevation of the attachment, representing the same as removed from the chair, except that a portion of the rocker to which the device is attached is shown in cross section; Fig. 3 is a perspective showing a portion of a rack and means for guiding the same, which constitutes a feature of the invention; Fig. 4 is a cross section through the driving shaft and illustrating a part of the driving mechanism for the fan; and Fig. 5 is a view similar to Fig. 4, further illustrating the driving mechanism.

Referring more particularly to the parts, and especially to Fig. 1, 1 represents a rocking chair of any suitable construction, having rockers or runners 2. To one of the runners near the rear extremity thereof, I attach rigidly an upwardly extending frame bar 3, which bar is formed near its upper end with an arm 4, which is attached to the side of the chair, as indicated, and above this point the bar 3 is offset outwardly so as to form a head 5. This head 5 is provided on each side with bearing brackets 6, which facilitate the mounting of a fan shaft 7, the same being disposed in a horizontal position and carrying a fan 8 of the ordinary propeller type. The fan shaft projects, as indicated, at the extremity opposite to the fan, and is pro-

vided with belt pulleys 9 and 10 respectively, which are rigidly attached thereto. At an intermediate point on the height of the frame bar 3 a bracket 11 is rigidly attached, and this bracket affords means for supporting a driving shaft 12, which is also in a horizontal position. This driving shaft is provided with two driving pulleys 13 and 14, the construction of which is shown very clearly in Figs. 4 and 5. Each driving pulley comprises a hub 15, which is rigidly attached to the shaft, and on this hub there is loosely mounted and guided a rim 16. The rim 16 is formed at its inner portion into a ring 17, which constitutes a clutch member. The hub 15 is provided with a clutch pawl 18, which is disposed in an inclined position as shown, and the end of this pawl is held against the inner face of the clutch ring 17 by a spring 19, as indicated. The construction of the two pulleys is identical except that the position of the pawl is reversed in one case, as will be seen by a comparison of Figs. 4 and 5. From this arrangement, it will be understood that when the shaft is rotated toward the left as indicated by the arrow in Fig. 4, the pawl 18 will jam on the clutch ring 17 and rotate the rim of the pulley. When the shaft is rotating in the opposite direction, this pawl 18 slips idly on the clutch ring, and does not produce any rotative effect. The frictional contact between the pawl and the ring is sufficient to produce the rotation described.

In Fig. 5 a reverse arrangement is found, the shaft operating to drive the pulley by a right-hand rotation, and slipping with a reversed or left-hand rotation. The pulley 13 is in alignment with the pulley 9, and is connected therewith by an open belt or cord 20. The pulley 14 is in alignment with the pulley 10, and is connected therewith by a twisted belt or cord 21. From this arrangement it should be understood that when the mechanism is in operation, both the pulleys 13 and 14 will drive their belts in opposite directions, and the twist in the belt 21 operates in effect to reverse its direction of movement at the fan shaft 7, so that both belts tend to rotate the shaft 7 in the same direction.

I provide means for alternately driving the driving shaft 12 in different directions. For this purpose, this shaft is provided with a rigid pinion 22, and with this pinion meshes a rack 23, which rack is provided on its rear side with a suitable guide 24 formed on the end of a bracket or arm 25, which is rigidly

attached to the frame bar, as will be readily understood. The lower end of this rack 23 has pivotally attached thereto a link 26, and the lower end of this link is pivotally attached to a floor lever 27. This floor lever lies in a horizontal position on the floor on the outer side of the runner to which the frame bar 3 is attached, and its forward end is pivotally attached to the rocker at the point 28, as indicated most clearly in Fig. 1. Under its rear end a roller 29 is provided, and above this roller a weight 30 operates to hold the lever normally on the floor. As the rocking chair rocks back and forth, a reciprocating movement of the rack 23 is produced by the floor lever 27, which remains substantially stationary at its rear end, and thus an alternate rotation of the shaft 12 is produced. This alternate rotation produces a continuous rotation of the shaft 7 in the manner described above, and hence a high velocity of rotation may be given to the fan 8. In this way an air current is directed toward the person sitting in the chair.

Special attention is called to the fact that the fan attachment does not in any way interfere with the freedom of moving the chair from place to place about the floor. The fan is provided with a suitable light metal guard which may be attached in any desired manner such as that shown.

Having thus described my invention, I claim as new and desire to secure by Letters Patent:

1. A rocking chair in combination with a weighted floor lever pivotally attached thereto and resting upon the floor, a frame bar attached to the chair, a driving shaft, means

for rotating said driving shaft in either direction from said floor lever, one-way clutches 40 on said driving shaft having pulleys driven respectively in opposite directions, a fan shaft, means for driving said fan shaft from both of said pulleys, and a fan carried by said fan shaft.

2. A rocking chair in combination with a weighted member resting upon the floor, a rack attached to said member and actuated thereby, means for guiding said rack, a driving shaft, a pinion carried thereby and meshing with said rack, one-way clutches carried by said driving shaft, a fan shaft, means for driving said fan shaft continuously in one direction from said clutches, and a fan on said fan shaft.

In testimony whereof I have signed my name to this specification in the presence of two subscribing witnesses.

WILLIAM SCHEURER.
